ELECTRIC RANGE

Jack Morgan, Chicago, Ill., assignor, by mesne assignments, to Radio Corporation of America, New York, N. Y., a corporation of Delaware

Application November 7, 1952, Serial No. 22,181

Term of patent 3½ years

(Cl. D81—25)

To all whom it may concern:

Be it known that I, Jack Morgan, a citizen of the United States, residing at Chicago, in the county of Cook and State of Illinois, have invented a new, original, and ornamental Design for an Electric Range, of which the following is a specification, reference being had to the accompanying drawing, forming a part thereof.

In the drawing, the figure is a perspective view of an electric range, showing my new design, the opposite side of the range being substantially the same as that shown.

The dominant features of my design reside in the portions shown in full lines.

I claim:

The ornamental design for an electric range, substantially as shown and described.
